United States Patent Office.

FREDERIC G. COCHRAN, OF ST. LOUIS, MISSOURI.

Letters Patent No. 102,777, dated May 10, 1870.

HEATING-STOVE.

The Schedule referred to in these Letters Patent and making part of the same

To all whom it may concern:

Be it known that I, FREDERIC G. COCHRAN, of St. Louis, in the county of St. Louis and State of Missouri, have invented a new and useful Improvement in Stoves, Ranges, &c., and I do hereby declare that the following is a full, clear, and exact description thereof, which will enable others skilled in the art to make and use the same, reference being had to the accompanying drawings forming part of this specification, in which—

Figure 1 is a vertical cross-section of a stove, illustrating my improvement, taken through the line *x x*, Figure 2.

Figure 2 is a vertical longitudinal section of the same, taken through the line *y y*, fig. 1.

My invention has for its object to improve the construction of stoves, furnaces, heaters, ranges, &c., for burning coal, peat, or other gaseous or fuliginous fuel, in such a way that the gases and other combustible products of said fuel may all be consumed instead of being carried off into the smoke-flue or chimney, as is the case with ordinary stoves, and

It consists in the construction and combination of various parts of the stove, as hereinafter more fully described.

A represents an ordinary stove, of which—

B is the fire-box;

C is the grate, and

D is the ash-pit, or drawer.

In the upper part of the stove A, at a suitable distance above the grate C, is secured an iron box or retort, E, which is made close, and which is provided with a close door, F, directly opposite a close door, G, in the upper part of the stove A.

The box or retort is made with a sliding bottom, H, which may be drawn out wholly or partly to allow the contents of said box or retort to drop into the fire-box B.

There are two or more pipes, the ends of which extend down through the fire-box B, and to, or nearly to, the grate C.

The pipes I extend up the sides and over the top of the box or retort E, and communicate with said box or retort E through holes in its top, and in the under side of the top parts of said pipes, as shown in figs. 1 and 2.

In using stoves, heaters, furnaces, &c., with my improvement attached, the retort or box E has a sufficient quantity of the fuel placed in it through the doors G F, the said two doors allowing the retort to be opened for the introduction of more fuel while the fire is burning, without allowing the smoke and gas to escape into the room.

The doors F G are then closed and a fire is made in the fire-box B in the ordinary manner.

As the fire in the fire-box B becomes hot the box or retort E is heated, and the smoke, gas, and other volatile products of the fuel in said retort are driven off, and, having no other way to escape, they pass down through the pipes I, and are discharged in the lower part of the fire-box B, and have to pass up through the fire, in which passage the combustible parts are consumed, and the incombustible parts escape through the upper part of the stove A and through the pipe J into the chimney.

By the time the fire in the fire-box B burns low, the retort E will be filled with a red-hot mass of thoroughly coked fuel. The fire in the fire-box B is then raked down, and the sliding bottom H of the retort E drawn partly out, allowing the most of the coke to drop into the fire-box B, a part of said coke being left upon the undrawn-out part of the sliding bottom to assist in starting the next supply of fuel.

The bottom H is then slid into its place, and another supply of fuel introduced into the said retort E, and so on indefinitely.

Having thus described my invention,

I claim as new and desire to secure by Letters Patent—

1. The retort E, having close door F and sliding bottom H, combined with stove A, having close door G, the pipes I I, and the fire-box B, all relatively arranged as and for the purpose described.

2. A retort, having a sliding bottom, combined with a stove, as and for the purpose specified.

The above specification of my invention signed by me this 14th day of February, 1870.

FREDERIC G. COCHRAN.
